INVENTOR—

George N. Smith,
By C. E. Humphrey
ATTORNEY.

UNITED STATES PATENT OFFICE.

GEORGE N. SMITH, OF AKRON, OHIO.

BAKING-IRON.

1,292,658.

Specification of Letters Patent. Patented Jan. 28, 1919.

Application filed June 13, 1918. Serial No. 239,763.

To all whom it may concern:

Be it known that I, GEORGE N. SMITH, a citizen of the United States, residing at Akron, in the county of Summit and State 5 of Ohio, have invented new and useful Improvements in Baking-Irons, of which the following is a specification.

This invention relates to improvements in baking irons especially adapted for use in 10 restaurants, at picnics, etc., for the serving of small orders quickly and economically.

The object of the invention is to provide such an iron containing one or more compartments and in the case of a plurality of 15 compartments each of the compartments is separate from the adjacent compartment so that each constitutes a separate unit to the end that each may be used independently of the other or one or both used simultaneously.

20 With the foregoing and other objects in view, the invention consists in the novel construction, combination and arrangement of parts constituting the invention to be hereinafter specifically described and illustrated 25 in the accompanying drawings which form a part hereof wherein is shown the preferred embodiment of the invention, but it is to be understood that changes, variations and modifications can be resorted to which 30 come within the scope of the matter hereinafter claimed.

In the drawings in which similar reference numerals indicate like parts in the different figures,

35 Figure 1 is a view of a simple form of a device embodying the present invention showing the device in its open position.

Fig. 2 is a view similar to Fig. 1 showing the device in its closed or operative position.

40 Fig. 3 is a view taken on line 3 of Fig. 5 of a baking iron embodying the present invention.

Fig. 4 is a view similar to Fig. 3 taken on line 4 of Fig. 5.

45 Fig. 5 is a rear view of the upper portion of the device with portions thereof broken away to better illustrate the construction of the interior thereof, and

50 Fig. 6 is a perspective view of a portion of one of the pans.

The device comprises a supporting frame embodying supporting legs 1, 2, 3 and 4. Extending between the pairs of legs 1 and 2 is a combined brace and shield 5 and a 55 similar shield 6 extends between the legs 3 and 4. Near the upper portion of the legs

1 to 4 inclusive is a drip pan 7 and near the lower portions of the legs is a horizontal table or shelf 8.

Mounted on the legs 1 to 4 inclusive is the 60 stove portion of the device and it comprises

a rectangular frame preferably of cast metal in a single piece and embodies a front wall 9, end walls 10 and 11 and a rear wall 12.

Extending between the walls 9 and 12 and 65 midway between the end walls 10 and 11 is an integral partition 13 (see Fig. 5).

The outer faces of the walls 9 to 12 inclusive are preferably inwardly and upwardly inclined upon curvilinear lines and the lower 70 portions of these walls overlap the upper outer portions of the legs 1 to 4 inclusive

and are secured thereto by bolts or screws 14. The inner faces of the upper portions of the walls 9 to 12 inclusive and the partition 13 are inwardly and downwardly 75 inclined to form faces 15 which terminate in

inwardly-extending flanges 16 which form seats for a purpose to be later described.

The upper edge of the wall 9 is provided 80 with notches 17 into which the handle or

handles employed for manipulating the lids of the pans may seat. The partition 13

serves to divide the space inclosed by the walls 9 to 12 inclusive into two compartments and the rear wall 12 of one compartment

is provided with notches 18 and the other compartment with notches 19. This

wall is furthermore provided with a plurality of slots 20. The inner face of the 90

upper portion of the rear wall near the central part of each compartment is provided with an inwardly-extending lug 21 adjacent

to which is a socket 22 forming a seat for a bifurcated bracket 23 which serves as a 95

support for an ordinary gas burner 24 which is supplied with gas through a supply pipe

25 supported by brackets 26 secured by bolts 27 to the lower portion of the wall 9 of the stove portion. The flanges 16 extending in-

wardly from the various walls of the stove portion serve as seats for the baking irons with which the cooking is done and these

baking irons may be of various types suitable for the class of work for which they

are intended. The baking iron in one compartment is provided with rearwardly-extending ears 57 arranged to coöperate

with companion ears 28 on lids 29 employed for closing the baking irons during the cook-

ing of the food. These baking irons are

adapted to seat on the flanges 16 and the

105

110

pairs of ears 57 and 28 of each iron are arranged to project through the notches 18 and 19 in the rear wall 12 of the stove portion of the device. The upper face of each 5 lid is provided with a pair of lugs 30 forming a socket into which may be inserted the shank end of an operating handle 31 which is removable so as to be utilized for any of the lids employed on the iron. The ears 57 10 on the baking irons are pivotally connected with the ears 28 through the medium of a removable pin 32 so that the lids may be utilized with any of the baking irons required. In Fig. 1 is shown a baking iron 15 commonly employed for frying eggs for making egg sandwiches and forms a very narrow space between it and the floor of the iron. This iron, of course, may be utilized for cooking any comparatively thin article 20 of food. In Fig. 1 is also shown a baking iron 34 of greater depth and containing a tray 35 divided into a plurality of compartments which is utilized for vegetables or other food products and this may be seated 25 on the iron 33. In the case of the baking iron 34 the cover 36 thereof is provided with longer ears 37 to enable the underside of the lid 36 to fit snugly over the upper face of the iron 34. Each of the baking irons 30 is formed near the ear 57 thereof with a trough 67 extending rearwardly through the respective notch 18 or 19 of the rear wall 12 closely adjacent to the ear 57 and projecting a sufficient distance so that any surplus fat 35 or grease accumulating in the iron may flow through this drain into a longitudinally-extending trough 38 which is provided with ears 39 engaging in the slots 20 in the wall 12. The surplus fat accumulating in this 40 trough 38 is collected in any suitable receptacle.

The provision of the present device affords a simple, cheap and economical method for cooking small quantities of food for restaurants, lunch counters, flats, kitchenettes, etc., especially where quickly served lunches are required.

I claim,

1. The combination in a device of the 50 character described of a hollow frame the inner faces of the walls of which are provided with flanges constituting seats, one of

the walls provided with notches, and a baking iron adapted to be removably mounted on said seat, said baking iron comprising a 55 pan-like lower member provided with a drain trough extending through one of said notches the side wall of said trough constituting an ear, said lower member also provided with a second ear, a lid or cover arranged to coöperate with said lower member and provided with ears pivotally united with the ears on said lower member and extending through the notches in said wall. 60

2. The combination in a device of the 65 character described of a hollow frame the inner faces of the walls of which are provided with flanges constituting seats, one of the walls provided with notches, and a baking iron adapted to be removably mounted 70 on said seat, said baking iron comprising a pan-like lower member provided with a drain trough extending through one of said notches the side wall of said trough constituting an ear, said lower member also provided with a second ear, a lid or cover arranged to coöperate with said lower member and provided with ears pivotally united 75 with the ears on said lower member and extending through the notches in said wall, 80 and a heating instrumentality below said lower member.

3. The combination in a device of the 85 character described of a hollow frame the inner faces of the walls of which are provided with flanges constituting seats, one of the walls provided with notches, and a baking iron adapted to be removably mounted on said seat, said baking iron comprising a pan-like lower member provided 90 with a drain trough extending through one of said notches the side wall of said trough constituting an ear, said lower member also provided with a second ear, a lid or cover arranged to coöperate with said lower member and provided with ears pivotally united 95 with the ears on said lower member and extending through the notches in said wall, a removable duct positioned along the notched wall arranged to receive the material discharged from said trough. 100

In testimony whereof I have hereunto set my hand.

GEORGE N. SMITH.
